(57) **CLAIM**

We claim the ornamental design for a 2-in-1 balance scooter bike, as shown and described.

DESCRIPTION

FIG. 1 is a perspective view of a 2-in-1 balance scooter bike embodying the invention.

FIG. 2 is a first side elevation view of a 2-in-1 balance scooter bike shown in FIG. 1.

FIG. 3 is a second side elevation view of a 2-in-1 balance scooter bike shown in FIG. 1.

FIG. 4 is a top plan view of a 2-in-1 balance scooter bike shown in FIG. 1.

FIG. 5 is a bottom plan view of a 2-in-1 balance scooter bike shown in FIG. 1.

FIG. 6 is a front elevation view of a 2-in-1 balance scooter bike shown in FIG. 1; and,

FIG. 7 is a rear elevation view of a 2-in-1 balance scooter bike shown in FIG. 1.

The broken lines shown in the drawings illustrate portions of the 2-in-1 balance scooter bike that form no part of the claimed design.
